UNITED STATES PATENT OFFICE

ALEXIS F. GILLET, OF OMAHA, NEBRASKA, ASSIGNOR TO JUBILEE MANUFACTURING CO., OF OMAHA, NEBRASKA, A CORPORATION OF NEBRASKA

WARNING SIGNAL

Application filed January 15, 1932. Serial No. 586,737.

The present invention relates to warning signals and the like, and more particularly to a signal or sounding device adapted to be operated by fluid pressure, such as air.

5 The invention aims to provide a novel construction of sounding or warning signal or device which may be connected to the intake manifold of an internal combustion engine for operating the signal from the suction in the intake manifold, and to provide an improved structure of the body part or bracket of the device which may be connected directly, or otherwise, with the intake manifold for operating the device.

15 Another object of the present invention is to provide a signal or sounding device of this character adapted to produce two or more tones, and to provide a controlling or valve means for the device by means of which 20 the tones may be simultaneously or consecutively sounded so as to produce the desired sounding or warning, such as to produce a high note and a low note.

A further feature of the present invention is to provide a novel construction of 25 sounding device or warning signal which may be constructed so as to simulate the bray of a donkey which is commonly called "hee-haw", and a sounding device which by a selection or interchange of the controlling valve 30 may be made to simulate the trumpeting of an elephant; the device being adapted to be used in advertising political and other like campaigns.

35 The invention also provides an improved construction of bracket which is relatively light, simple and of small size which provides a main connecting opening and a pair of branch openings with means for supporting horns or other fluid actuated sounding devices with respect to the branch openings, and which also embodies in its construction 40 a novel valve casing for removably supporting a valve so that the valve may be interchanged with other like valves having their communicating ports or openings disposed in various ways to effect different desired results.

With the foregoing and other objects in view, the invention will be more fully de-

scribed hereinafter, and will be more particularly pointed out in the claims appended hereto.

In the drawings, wherein like symbols refer to like or corresponding parts throughout the several views.

Figure 1 is a side elevation, partly in section, of a warning or sounding device constructed according to the present invention, the dotted lines showing interchanged positions of the high and low tone sounding devices or horns.

Figure 2 is a fragmentary sectional view taken through the body portion of the signal showing a modified form of valve therein.

Figure 3 is a fragmentary side elevation, partly in section of a motor vehicle having an internal combustion engine, and with a warning signal constructed according to the present invention mounted thereon.

Figure 4 is a vertical section taken through the warning signal showing a further modified form of valve applied thereto.

Figure 5 is a detail inner side view of the disc and reed of the larger sounding device.

Figure 6 is an edge view of the same.

Figure 7 is a lower or inner side view of the disc and reed of the smaller sounding device.

Figure 8 is an edge view of the same.

Figure 9 is a detail side elevation of the control valve shown in the modified form illustrated in Figure 4.

Figure 10 is an inner end view of the same.

Figure 11 is a detail side elevation of the form of valve shown in Figure 1, and

Figure 12 is a like view of the modified form of valve shown in Figure 2.

Referring now to the drawings, and first to Figure 3, 10 designates the body of a motor vehicle provided with a steering column 11 supporting the steering wheel 12 at its upper end, and 13 designates a hood within which is housed an internal combustion engine 14 of any suitable type and provided with an intake manifold 15.

The warning signal or sounding device comprises a body portion or bracket 16 which may be of substantially Y-shape, as shown in

55

Figures 1, 2 and 4, and which at its lower end is provided with an externally threaded main section 17 adapted to be tapped into the upper or other suitable portion of the manifold 15, as shown in Figure 3 so as to establish communication between the interior of the body bracket 16 and the manifold. The body bracket 16 is provided with a pair of upwardly diverging branches 18 which communicate at their lower ends with the main stem or section 17 and which are also externally threaded so as to receive thereover the inner ends of horn casings 19 and 20 which are detachably threaded or mounted upon the branches 18. The horns 19 and 20 are preferably made of different sizes with one horn 19 relatively large and the other horn 20 relatively small so that a low or deep tone may be produced with the larger horn 19 and 20 a higher pitched tone with the smaller horn 20.

As shown in Figures 4, 5 and 6, the larger horn 19 embodies a body part or casing which may be globular or of other suitable form and which may be made in sections meeting in a transverse middle plane and secured together by out-turned and interlocking flanges 21, as shown in Figure 4. A disc or plate 22 is fitted between the flanges 21 and held intermediate in the casing of the horn 19. The disc 22 is provided with a slot or aperture 23 at its intermediate portion which is closed by an overlapping reed or leaf 24 secured at one end by rivets 25, or the like, to the plate 22 for normally closing the opening 23. The leaf 24 has sufficient inherent resiliency to normally lie flat against the lower side of the disc 22 and is adapted to flex under the suction from the manifold 15, and is proportioned to vibrate and thus produce a relatively low or deep tone.

The smaller horn 20, as shown in Figures 4, 7 and 8, is provided with an intermediate disc 26 secured between the overturned and interlocking flanges 27 and the casing of the horn 20 in a manner similar to that shown at 21 in the larger horn, and the disc 26 is provided with a relatively small slot or opening 28 at its intermediate portion which is normally closed by a flexible reed or plate 29 secured by rivets 30 to the disc 26. As shown in Figure 7, the reed 29 and the opening 28 preferably taper toward the free end of the reed 29 so that a relatively high pitched sound or tone is provided by suction in the manifold 15. The branched body 16 is provided with a valve casing 31 as an integral part of the bracket 16 and which comprises an opening extending through the intermediate portion of the body 16 and intersecting the branches 18 at points which are spaced above the main stem 17 of the body. The purpose of this is that the valve casing 31 communicates independently at spaced points 65 with the branches 18 so that these branches

18 may be independently controlled by different valve structures mounted in the casing 31. The valve casing 31 extends in the form of hollow bushings or sleeves at the front or rear edges of the body bracket 16, as shown in Figure 4 particularly. 70

Different types of valves may be mounted in the casing 31. In Figure 1 a valve 32 is shown. This valve is shown in detail in Figure 11, and comprises a cylindrical rod 75 which may be solid, or otherwise, and of sufficient length to extend entirely through the valve casing 31 and beyond the inner end of the valve casing to support and expand the spring 33 which bears at one end against the forward end of the valve casing 31 and at its other end against a pin 34 or other suitable device carried on the valve rod 32 for normally urging the valve rod 32 forwardly in the casing. The rear end of the valve rod 32 80 is provided with a bail 35 or link to which may be attached a pull rod 36 of any suitable construction and which is slidably mounted upon a bracket 37 secured to the steering post 11 in suitable position beneath the steering 90 wheel 12. The rod 36 may have a pull ring 38 to facilitate the engagement and pulling of the rod 36 for retracting the valve 32 against the tension of the spring 33.

The valve rod 32 is provided with two apertures or openings 39 and 40 each of which are of suitable length and which are spaced apart a distance equal substantially to the distance between the brackets 18 at their points of intersection with the valve casing 31. The openings 39 and 40 are thus relatively positioned, and relatively proportioned so that when the valve rod 32 is drawn backwardly both of the ports 39 and 40 open simultaneously and the suction in the manifold 15 is communicated simultaneously to the horns 19 and 20 and effect the dual simultaneous sounding of the device. 100

Normally the ring 38 holds the valve rod 32 in a forward position so as to dispose the solid portions of the rod 32 in register with the branches 18 and thus cut off communication between the branches and the manifold. 110

A slight modification of the valve rod is shown in Figures 2 and 12. The valve rod 41 is provided with two passages or openings 42 and 43 which are widely spaced apart along the valve rod and which are so located that, in the normal closed position of the valve, the opening 42 lies between the branches 18 and the solid portions of the valve rod 41 are in register with the branches so as to close communication between the same and the manifold. The intermediate portion of the rod which lies between the openings 42 and 43 is relatively long so that as the valve rod 41 is drawn backwardly the opening 42 first registers with the rear branch 18 while the forward branch is still maintained closed. The intermediate portion of the valve rod 41 120 125 130

must pass rearwardly of the forward branch and consequently cut off both branches so as to silence the device prior to the registering of the opening 43 with the forward branch of the device. Thus, one of the horns such as the horn 20 is first sounded. There is then a period of silence during the further backward movement of the valve 41, and finally the larger horn 19 is sounded. The reeds 24 and 29 of the horns may of course be modified or changed or substituted by other suitable operating mechanisms to produce desired tones or noises when the valve is operated.

Figures 4 and 9 show another slight modification of the valve rod 44 wherein the valve rod is provided with openings 45, 46 and 47. The rear opening or port 45 of the valve rod is near the bail or link 35 so that upon the first movement of the valve rod 44 the horn 20 is operated, and upon the further movement of the valve rod 44 the warning is silenced and then the larger horn 19 is given two separate and distinct blasts with a short intermission therebetween. It is of course understood that these openings or ports in the various valve rods may be of any desired number and spaced along the valve rods in any desired manner so as to effect the desired sounding of the horns 19 and 20.

As shown in dotted lines in Figure 1, the horns 19 and 20 may be interchanged so that by the use of the same valve rod or rods an opposite effect may be obtained.

If a valve stem is employed, such as shown at 41 in Figures 2 and 12 a "hee-haw" sound will be produced by moving the valve rod 41 rearwardly until the annular notch or port 42 permits communication between the rear branch 18 and the main stem 17 of the valve casing, sounding the small horn 20 and producing a tone simulating the "hee". Further rearward movement of the valve rod 41 cuts off the above described communication between the rear branch 18 and the manifold, and brings the annular notch or port 43 into register with the forward stem 18 to establish communication between the same and the manifold 15, and operating the horn 19 to produce the proper or deeper tone "haw", completing the desired signal or sound.

In each instance the spring 33 returns the valve rod to normally closed position when the rod 36 is released. In the same manner, the horns may be proportioned or modified to simulate the trumpeting of an elephant or any other desired sounds or combinations thereof, within the limits of the structure.

It is obvious that various changes and modifications may be made in the details of construction and design of the above specifically described embodiment of this invention without departing from the spirit thereof, such changes and modifications being restricted only by the scope of the following claims.

What is claimed is:

1. A sounding device, comprising a body portion adapted for connection with a source of suction and having independent passages therein, sound producing devices mounted on the body portion in independent communication with the passages, and a longitudinal slide valve mounted in the body portion and having ports therein spaced lengthwise of the valve for registration with the passages in predetermined order during the movement of the valves. 70

2. A warning signal, comprising a pair of sounding devices, a body portion connected to said sounding devices and having independent spaced apart passages therein and adapted for connection with a source of suction, and a valve mounted in the body portion for longitudinal movement and in intersecting relation with said passages, said valve having ports therein spaced lengthwise of the valve for predetermined register with the passages as the valve is moved. 75

3. A warning signal, comprising a body portion adapted for communication with a source of suction and having spaced passages therein, sounding devices connected to said body portion and communicating independently with said passages, and a rod valve slidably mounted in the casing in intersecting relation to said passages and having ports therein spaced lengthwise of the rod valve for predetermined register with said spaced passages during the longitudinal movement of the valve. 80

4. A warning signal, comprising a bracketed body portion having a main stem and branches communicating therewith, said main stem adapted for connection with a source of suction and said branches adapted for connection with sounding devices, said body portion having a valve casing therein intersecting at spaced points said spaced branches, and a rod valve slidably mounted in the valve casing and having spaced ports therein adapted to register in predetermined order with said passages during the longitudinal sliding movement of the valve. 85

5. A warning signal adapted for attachment to a motor vehicle having a combustion engine and an intake manifold, comprising a branched body portion adapted to be threaded into said manifold, a pair of horns mounted on the branches of the body portion with one of said horns being of higher pitch than the other, a slide valve mounted in said body portion intersecting the branches thereof and having ports therein adapted to register in predetermined order with said branches when the valve is moved through the body portion, a spring disposed between the body portion of the valve for normally urging the valve into a forward closed position, a pull rod connected to the rear end of the valve, and means for supporting said pull. 90

120

125

130

rod on the steering column of the vehicle in position of easy access for drawing said rod and shifting said valve.

6. A warning signal for application to the intake manifold of an internal combustion engine, comprising a substantially Y-shaped body portion having a main stem adapted to be threaded into the manifold and having its branches threaded to receive independent horns thereon, a rod valve slidably mounted in said bracket and intersecting the branches thereof, a spring carried by the valve and engaging the bracket for normally holding the valve closed, and manual means connected to the valve for moving the same against the tension of said spring, said valve having ports spaced lengthwise in the valve for predetermined register with said branches to actuate said horns.

20 7. A warning signal, comprising a body bracket having a threaded stem on its lower end adapted to engage in an intake manifold to support the bracket and establish communication with the manifold, said bracket having a pair of upstanding branches communicating with the stem and adapted to receive thereon independent horns, a valve casing structure embodied in the intermediate portion of said body bracket and having sleeve portions extending from the forward and rear edges thereof, said casing structure intersecting said branches of the body bracket at spaced points, a rod valve slidably mounted in the casing body and projecting from the forward and rear ends thereof, a spring on the rod valve for holding the rod valve in forward position, manual means connected in the rod valve to draw the same rearwardly, said rod valve having spaced ports disposed therein to normally close said branches and adapted upon movement of the valve to establish communication between the branches and the stem in desired order for effecting the independent and simultaneous operation of the horns.

8. A warning signal comprising a plurality of suction operated horns, a bracket supporting said horns and having interior passages therein communicating with the horns and adapted for connection to a source of suction to operate the horns, said bracket having a transverse passage therethrough intersecting the interior of the bracket, a rod slidably mounted in the transverse passage and conforming in cross sectional size and shape thereto, a spring carried on one end of the rod and engaging the bracket to hold the rod normally and yieldingly in one longitudinally shifted position for closing the source of suction to said horns, said rod having a reduced portion providing an opening therein, and means for shifting said rod against the tension of the spring to bring the opening in the rod into register with the point of intersection of the interior of the

bracket with the transverse passage and open the source of suction to said horns.

9. A warning signal, comprising a plurality of suction operated horns, a bracket having interior passages communicating with the horns and adapted for connection with a source of suction, said bracket having a transverse passage therethrough intersecting the interior of the bracket, a slidable rod extending through the transverse passage to close communication between the source of suction and the horns, said rod having a reduced portion and adapted to be shifted longitudinally to register the reduced portion with the point of intersection between the transverse passage and the interior of the bracket to establish communication between the horns and the source of suction.

In testimony whereof, I have affixed my signature.

ALEXIS F. GILLET.
